UNITED STATES PATENT OFFICE.

JAMES LOGAN GILMORE, OF SHARPSBURG, IOWA.

DESIGN FOR A HOG-PEN.

SPECIFICATION forming part of Design No. 26,228, dated October 27, 1896.

Application filed August 6, 1896. Serial No. 601,929. Term of patent 14 years.

To all whom it may concern:

Be it known that I, JAMES LOGAN GILMORE, a citizen of the United States, residing at Sharpsburg, in the county of Taylor and State 5 of Iowa, have invented and produced a new and original Design for a Hog-Pen; and I do hereby declare the following to be a full, clear, and exact description of the invention, such as will enable others skilled in the art to which 10 it appertains to make and use the same.

In the drawings, Figure 1 shows a perspective view of a hog-pen constructed according to this invention. Fig. 2 is a side view drawn to a smaller scale.

15 The leading feature of the design consists of a hollow pen or house of pyramidal form provided with a front side which is narrower than the rear or back and which has an opening in front through which access may be had 20 to the interior. The pen does not taper to a point, but is flat on top and has a triangular opening for ventilation which communicates with its hollow interior.

A is the pyramidal pen or house. The sides ²⁵ *a a'* are substantially triangular in form and converge toward the front *b*, which is narrower than the back *c*. The sides *a a'* are of about the same area as the back *c*, and the sides, back, and front are joined together in pyramidal form. ³⁰

B is an opening at the lower part of the front, through which access may be had to the interior of the house or pen. This opening may be provided with one or more doors of approved construction. ³⁵

C is an opening at the top of the house for ventilation.

What I claim is—

The design for a hog-pen substantially as hereinbefore described and shown. ⁴⁰

In testimony whereof I affix my signature in presence of two witnesses.

JAMES LOGAN GILMORE.
